UNITED STATES PATENT OFFICE

JOHN S. NAIRN, OF DETROIT, MICHIGAN

AMUSEMENT DEVICE

Application filed June 18, 1930. Serial No. 461,887.

This invention relates to an amusement device and contemplates particularly a device that can be used as a merry-go-round and what is commonly known as an ocean wave.

5 The broad idea of this type of device is shown in my previous United States Patent 1,658,733 and this invention contemplates several specific improvements on the device therein shown and described. In the device 10 shown in the above patent the operating gears and shaft are placed above the beam. This arrangement has proved somewhat unsatisfactory in that the thin longitudinal shaft is often grasped by a child to assist him in 15 mounting the beam resulting in the bending of the shaft which in turn displaces the gears. Further, this arrangement of the shaft and gears above the beam precludes the possibility of mounting additional seats on the beam in 20 case three or four children wish to operate the device rather than merely two because the necessary additional space on the beam is occupied by the operating gears and shafts.

It is an object of this invention to overcome 25 these disadvantages and this has been achieved by mounting the longitudinal shafts and operation gears beneath the beam.

In my previously described and patented 30 device the elliptical gears and associated pinion were found to wear after a certain amount of use, and hence, tended to come out of mesh which rendered the device inoperative. It is an object of the invention to overcome this 35 disadvantage and this has been achieved by at all times yieldably holding the elliptical gears in mesh with the pinion.

In the above patent there is also disclosed 40 a temporary support member for maintaining the beam in a horizontal position while the children are getting into the seats. The device is so constructed that by pulling downwardly on the handle, the handle serves as a bar to lock the child into the seat and simultaneously raises the collapsible supports to 45 permit the beam to operate in its predetermined path. A disadvantage of this arrangement was that one child would draw down on the lever and lock himself in before the other child had seated himself, consequently the beam would swing into operation. To over-

come this disadvantage is a further object of this invention and this has been achieved by providing each support with a locking mechanism, each of which must be released before the supports can be raised and either 55 seat locked.

An object of the invention is to positively 60 guide the lower end of the vertical pivoted shaft.

A further object of the invention is to provide 65 the beam with a suitable counter-balancing mechanism.

A further object of this invention is to provide 70 a positive locking mechanism for locking the vertical shaft in whatever angular position desired to in turn operate the beam in a plane at an angle to the horizontal.

In the drawings:

Fig. 1 is an elevation showing the amusement device in inoperative position.

70 Fig. 2 is a view along the line 2—2 of Fig. 1.

Fig. 3 is a fragmentary detail of the gear and pivoted shaft elements.

Fig. 4 is a section along the line 4—4 of 75 Fig. 3.

Fig. 5 is a vertical section along the line 5—5 of Fig. 3.

Fig. 6 is a section along the line 6—6 of 80 Fig. 5.

Referring more particularly to the drawings, it will be seen that the device comprises 85 a beam 1 that is rotatively and pivotally mounted upon a suitable support 2. The beam 1 has located at each end thereof a seat portion 3, each seat portion being provided 90 with a suitable side and back frame work 4. As shown in Fig. 1 the beam 1 is horizontally positioned and is maintained in this position by the supports 5. The supports 5 are each pivotally mounted as at 6 adjacent an end of 95 the beam. The pivot supports 5 are connected to each other so as to collapse simultaneously upwardly and under the beam by means of the longitudinally slidably shafts 7 and 8 which are slidably mounted on the bottom of the beam by means of the brackets 9 and 10 respectively and which are joined by the lazy tongs 11. The shaft 7 is connected to the support 5 by the link 12 and the support 5a is connected to the shaft 8 by the link 100

13. Each of the supports 5 and 5a have fixed thereto the L-shaped levers 14 and 15 respectively. The levers 14 and 15 are arranged to be grasped by the child seated in the seat and pulled downwardly whereupon the levers 14 and 15 engage in suitable notches in the seat frame backs 4 and form a horizontal locking bar across the front of the seat to lock the child in the seat as is described in my above mentioned patent.

10 To prevent a child from getting into one of the seats and operating either of levers 14 or 15 which causes the supports 5 and 5a to collapse under the beam before the other child is seated in the seat, I propose to provide each of the pivoted supports 5 and 5a with a locking member. This locking member takes the form of the bars 16 and 17 which are respectively pivoted as at 18 and 19 to 15 the supports 5 and 5a. Each of the bars 16 and 17 is provided with a notch 20 and 21 respectively which are arranged to engage suitable looped brackets 22 and 23 mounted each on an end of the beam 1. As shown in 20 Fig. 1 the locking bars 16 and 17 engage the brackets 22 and 23 in the notches 20 and 21 respectively which in turn locks the supports 5 and 5a against pivotal movement. Owing to the shaft and lazy tongs connection between the supports 5 and 5a neither of these 25 supports can be collapsed under the seat by either child operating the levers 14 or 15 so long as one of the bars 16 and 17 is in locked relation. Hence, this arrangement requires that each child be seated in his respective seat and that both of the bars 16 and 17 be raised out of locking engagement with the brackets 22 and 23 before the levers 14 and 15 can be 30 actuated to collapse the supports 5 and 5a and lock the children into the seats.

35 Since it is necessary to have the beam rotatably mounted on the support 2, to this end the beam 1 is provided with a suitable bossed centrally positioned plate 25 which is secured 40 to the beam 1 by any suitable means such as the screws 26. The support 2 is provided with suitable opposed bearing sockets 27. These bearing sockets 27 are arranged to receive the trunnions 28 which 45 are fixed to the depending bossed portion 30 of the nonrotatable bevel gear 31. Hence, the bevel gear 31 is free to pivot upon the support 2 by the engagement of the trunnions 28 in the bearing sockets 27. The gear 31 has a 50 central opening 32, the beam 1 an opening 34, and plate 25 an opening 35 through which is passed the vertical shaft 36. A suitable bearing race 37 is interposed between the bevel gear 31 and the beam 1 and surrounds the shaft 36. The shaft 36 is arranged to be keyed to the plate 25 by the removable key 38.

55 The support 2 is preferably a pyramid frame of angle iron. The frame 2 has secured thereto a suitable horizontally positioned support 40 which may be a rectangular plate

of metal extending lengthwise across the frame 2 substantially midway between the top and bottom thereof. The support plate 40 has a suitable slot 41 running lengthwise thereof through which projects the shaft 36. 60 Since the shaft 36 pivots backwardly and forwardly with the beam 1 the slot 41 serves as a guide therefor. The plate 40 also rotatably supports the elliptical gears 42 and 43. The gears 42 and 43 are swiveled to the support 40 eccentrically as at 44 and 45 respectively. The shaft 36 has fixed thereto the pinion 46 which is arranged to mesh with each of the elliptical gears 42 and 43 as shown.

65 As the teeth of the elliptical and pinion gears wear there is a tendency for the same to unmash and hence the elliptical gears will not remain in proper alignment to permit operation of the elliptical gears and pinion to oscillate the beam upwardly and downwardly as will be described below. To prevent this contingency the shaft 36 has rotatably mounted thereon the collar 47. Each end of the collar 47 is connected to the geometrical center of the elliptical gears by means of the coil springs 48 and 49 respectively. These springs at all times yieldably hold the elliptical gears in mesh with the pinion 46.

70 The plate 40 serves as a plate upon which slides the angle plate slide 52 provided with an opening 53. The slide 52 also has an opening 54 centrally thereof through which rotatively projects the lower end of the shaft 36. The plate 40 is provided with a series of 75 openings 51. The holes 51 and 53 permit the slide 52 to be adjusted along the plate 40 and locked in whatever position desired by a suitable locking key 55. Movement of the slide 52 along the plate 40 and keying the same thereto adjusts the shaft 36 and consequently the beam 1 in whatever angular position desired owing to the trunnion engagement of the gear 31 with the frame 2 in the sockets 27.

75 Since it is desirable to rotate the beam 1 upon the frame 2 by means of the intervening gear 31 and bearing race 37 suitable mechanism is provided which takes the form of the shafts 60 and 61. These shafts are mounted lengthwise beneath the beam 1 upon suitable journal brackets 62. The shaft 60 has fixed at each end thereof the pinion gears 63 and 64 respectively and shaft 61 has fixed at each end thereof the pinion gears 65 and 66 respectively. The pinions 64 and 65 mesh with the non-rotatable bevel gear 31. The beam has suitably journaled therein the upright shafts 67 and 68 each of which has a horizontally rotatable crank handle 69 at the upper end thereof and a pinion gear 70 at the bottom end thereof, the pinion gears 70 being in mesh with the gear 63 and 66.

80 Owing to the fact that the beam 1 is pivoted on the support frame 2 by the trunnion

28 the center of the beam is spaced upwardly from the trunnion 28. Hence, when the beam is in the tipped position shown in Fig. 3 the center of the beam and consequently the greater portion of the weight of the beam and gear mechanism will be to the left of the trunnion 28; this requires the operator of the crank on the seat to the right of the trunnion to initially overcome this additional weight. 10 This is an important factor because it is highly desirable to have the cranks 69 function as easily as possible. This has partially been achieved by having the cranks rotate in a horizontal rather than in a vertical plane 15 and has been further achieved by the use of the counter-balancing springs 70 and 71. These counter-balancing springs are secured at their outer ends as at 72 to the frame 2. The lower end of the shaft 36 is milled away 20 to provide a projecting pin 73 and a shoulder 74. The inner ends of the springs 70 and 71 are secured to a suitable collar 75 having a central opening for reception of the pin 73 on the end of the shaft 36. Hence, the collar 75 is held in position on the end of the shaft 36 yieldably by the springs 70 and 71.

As shown in Fig. 3 the shaft 36 is swung to the extreme limit right of its center position. When in this position the spring 71 is 30 completely collapsed so that it exerts no pull to the right on the collar 75 and shaft 36. At the same time spring 70 has reached the maximum of its tension. As the shaft 36 pivots toward the center the pull of the spring 70 gradually decreases and that of the spring 71 increases until the shaft reaches center whereupon each of the counter-balancing springs exert the same tension. As the shaft swings to the left of center the tension of the spring 70 decreases and that of the spring 71 increases until the shaft reaches the extreme position to the left of center whereupon the spring 70 is completely collapsed and the spring 71 is expanded to exert its 40 greatest tension.

As shown in Fig. 3 when the operator seated on the right hand seat turns the crank to pivot the beam 1 he is assisted by the pull of the counter-balancing spring 70 until the beam reaches a horizontal position. Further, this arrangement of the counter-balancing springs draws the beam 2 and maintains it in a horizontal position after the children get off the seats whereupon it is always in 50 the proper position for use.

As shown in the drawings the operation of the device is as follows:

After each of the seats is occupied by a child, each child must first release the locking bars 16 and 17 whereupon the levers 14 and 15 can then be pulled downwardly simultaneously to lock each child in the seats 3. Each child turns the crank 69 adjacent his seat whereupon the shafts 60 and 61 are rotated. Since the gear 31 is stationary, the

beam 1 is caused to rotate relatively thereto. As the beam 1 rotates, it likewise turns the shaft 36 since it is keyed thereto by the key 38. The turning movement of the shaft 36 through the pinion 46 causes the elliptical gears 42 and 43 to rotate about their respective pivots as indicated by the dotted lines (Fig. 4). The rotation of the elliptical gears causes the shaft 36 to move back and forth in the slot 41. This back-and-forth movement of the shaft 36 through the trunnion and socket arrangement between the stationary gear and frame causes the beam to pivot upwardly and downwardly. Since the beam is at the same time rotating this upward and downward pivotal motion of the beam cooperates with the rotary motion to form an ocean wave movement.

When it is desired to have merely a rotary motion of the beam 1, the beam and shaft are locked in whatever position desired by means of the slide 52 and key 55. Thereafter the pin 38 is removed. Hence, the beam 1 is now in rotative relation with the shaft 36. As the cranks 69 are turned the shaft and bevel gear arrangement 61 and 31 causes relative rotational movement between the beam 1 and the non-rotatable bevel gear 31 at whatever angle in which the beam 1 is positioned.

Although the means here shown for rotating the beam 1 about its pivot consists of the non-rotative bevel gear 31 and the associated pinion shafts and hand cranks, it is understood that other equivalent rotative means could be used, the main desideratum being a non-rotative member centrally located and pivoted to the support 2 and means for translating the rotary motion of the cranks 69 to the central member 1 which, owing to its non-rotatability, creates a relative rotational movement thereto in the beam 1.

In the claims the bevel gear 31 is broadly designated as a stationary pulley and the longitudinal shafts 60 and 61 and associated pinions as motion translating means. The terms pulley and motion translating means are used broadly to include not only the specific means shown but also such well-known equivalents as the belt and pulley, chain and sprocket, and multiple all gear arrangements.

What I claim is:

1. An amusement device comprising in combination of a support, a pulley and rotatable beam pivotally supported thereby, a shaft projecting through the said beam and pulley which shaft is arranged to be optionally keyed to the said beam and to rotatably engage the said pulley, a pair of elliptical gears rotatably supported by the said support, a pinion on the end of the said shaft arranged to mesh with said elliptical gears, and manually operable means operatively connected to the pulley and supported by the said beam whereby the manually operable means can be operated to effect an ocean wave

movement on the part of the beam when the shaft is keyed to the beam and to effect a simple rotary movement on the part of the beam when the shaft is not keyed to the said beam.

5 2. An amusement device comprising in combination of a support, a beam pivotally and rotatably mounted on the said support, a shaft having one end fixed to the said beam and the other end having fixed thereto a pinion, a pair of elliptical gears eccentrically and rotatably supported by the said support and arranged to mesh with the said pinion, means for rotating the said beam and shaft, and means for yieldably engaging the said elliptical gears to retain them in mesh with the said pinion.

10 20 3. An amusement device comprising in combination of a support, a beam pivotally and rotatably mounted on the said support, a shaft having one end fixed to the said beam and the other end having fixed thereto a pinion, a pair of eccentrically rotatable elliptical gears supported by the said support and arranged to mesh with the said pinion, and spring means connected to the said shaft and elliptical gears whereby the elliptical gears are at all times yieldably retained in mesh with the said pinion.

15 30 35 40 4. An amusement device comprising in combination of a support, a beam having a seat portion adjacent each end and arranged to move relative to the said support, a collapsible support adjacent each end of the said beam, means operatively connecting the said collapsible supports so that the collapsing or extending of the one simultaneously collapses or extends the other, means for collapsing the said supports, and a locking member secured to each support whereby each locking member must be unlocked before the supports can be collapsed beneath the said beam to permit operation of the beam.

45 45 50 55 5. An amusement device comprising in combination of a support, a beam having a downwardly projecting shaft pivotally mounted on the said support, a collar arranged to removably engage the lower end of the said shaft, a pair of counter-balancing springs connected at one end to the collar and the other end to the support whereby the said collar is yieldably retained in engagement with the said shaft.

55 60 65 70 6. An amusement device comprising in combination of a support, a beam having a depending shaft pivotally mounted on the said support, the said beam being arranged to rotate relative to the said support, an adjustable slide and track operatively connected to the said shaft whereby the shaft may be locked in any pivoted position to in turn permit rotation of the said beam in whatever plane desired.

65 7. An amusement device comprising in combination of a support, a beam having a

depending shaft pivotally and rotatably mounted on the said support, guide means for slidably engaging the lower portion of the shaft to guide the same as the shaft pivots back and forth.

70 In testimony whereof I affix my signature.
